UNITED STATES PATENT OFFICE.

GEORGE A. IMHOFF, OF GROW, OKLAHOMA.

SHOCK-LOADER.

1,080,345.

Specification of Letters Patent.

Patented Dec. 2, 1913.

Application filed March 15, 1910. Serial No. 549,568.

To all whom it may concern:

Be it known that I, GEORGE A. IMHOFF, a citizen of the United States, residing at Grow, in the county of Roger Mills and 5 State of Oklahoma, have invented certain new and useful Improvements in Shock-Loaders, of which the following is a specification.

The object of my invention is to produce 10 a shock loader that will pick up the shocks of corn, wheat, rye, etc., as they stand in the field, and automatically load them on a wagon.

A further object of my invention is to 15 automatically pick up hay, flax, etc., and load the same on a wagon; and with these objects in view, my invention consists of the parts and combination of parts as will be hereinafter pointed out.

20 In the drawings, Figure 1 is a top plan view of a shock loader embodying my invention; Fig. 2 is a side elevation of the same, parts being broken away; Fig. 3 is a detail sectional view on the line 3—3, Fig. 2; Fig. 25 4 is a front elevation of the loader; Fig. 5 is a top plan view of the lock for the teeth of the gathering wheels, and Fig. 6 is a detail perspective view of one of the gathering teeth. Fig. 7 is a perspective view of 30 one of the cams.

1 represents a frame to which the draft tongue 2 is secured in any suitable manner.

3 is a depending side member secured to the frame 1 and extending to a point comparatively close to the ground. This side member forms one side of the guideway to be hereinafter referred to.

4 is a traction wheel journaled on a spindle which is secured to the side frame 3.

40 5 is an elevator frame mounted on the main frame at a suitable angle and extending outwardly to one side of the machine, as shown in Figs. 1 and 4, said frame being provided with an endless carrier 6 of suitable construction; the carrier being mounted on suitable sprocket wheels 8 and 9. The shaft of the sprocket wheels 9 extends through the frame 5 at one end and is provided with a bevel gear wheel 10.

50 11 is a power shaft mounted in bearings 12, the inner end of the shaft being provided with a bevel gear wheel 13 which meshes with the bevel gear 10, and a sprocket wheel 14, on which the power chain 15 is mounted.

55 16 is a large sprocket wheel on which the

chain 15 is mounted, and by which said chain is driven from the axle of the traction wheel 17 to be hereinafter referred to.

18 is an endless carrier suitably mounted on the side frame at the rear of the machine 60 and provided with teeth 19. The endless carrier is provided with shafts at each end on which are mounted sprockets which are connected by suitable drive chains. The driving shaft 20 of the carrier 18 is provided 65 with a driving gear which meshes with the gear wheel 20^a mounted on a shaft 20^b carrying a pinion on which is mounted the drive chain 21, which is driven from a sprocket wheel 22 mounted on the shaft 11. 70

23 are arms extending transversely of the tongue at a suitable distance forward of the front of the machine. The outer ends of these arms are bent downward as at 24 to provide journals for the gathering wheels. 75 These gathering wheels are substantially conical and are each provided with a hub 25 from which depends a spindle box 26 on the lower end of which is secured a bevel pinion 27.

28 are spokes, one end of which is secured in the hub 25, while the other end is secured in a rim 28 which is suspended thereby. As shown in the drawing, there are two of these gathering wheels. The extreme 85 lower end of the arms 23 terminates in spindles on which the traction wheels 29 are journaled. These wheels 29 are of less diameter than the gathering wheels and are mounted within the gathering wheels, as 90 clearly shown in Figs. 1, 2 and 4.

30 are bevel gear wheels secured to the wheels 29 and mesh with the pinions 27 to revolve the gathering wheels. The rim of the gathering wheels is provided with a 95 number of depending gathering teeth 31 which are loosely mounted in said frame. These teeth are bent to form a right angle portion 32 which has a bearing in the rim 28' and is again bent at right angles to form the portion 33 which is substantially parallel with the inner face of the rim 28' and extends in the direction thereof, as shown in Fig. 5. 34 is a plate secured to the depending arm 24 and extending less than half the circumference of the rim 28'. This plate 34 bears on top of the portion 33 of the pins or teeth 31 and holds the pins rigid in order that they may perform their function of 100 gathering, but as soon as the teeth pass from

105 110

under said plate they freely swing in the rim 28' on the portion 32 and thus offer no resistance to objects in their path.

5 The traction wheel is journaled on a spindle 36 secured to the frame 1. This wheel is of greater diameter than the wheel 4, as will be seen in the drawing. The inner face of this wheel is covered by sheet iron or other suitable material 35 to prevent material 10 passing between it and the side 3 from passing through said wheel.

15 37 is a disk mounted on the spindle of the wheel 17, on the periphery of which are a number of pairs of lugs or ears 38 between which spokes 39 are pivoted by means of the bolts 40.

20 41 is a ring secured to the outer face of the wheel 17 by means of the tubular spacing members 42, said members being provided with an elongated slot 43.

25 44 are flanged rings fitted over the spacing members and riveted thereto by means of the rivets 45. 46 are bolts securing the spacing members to the wheel 17 and ring 41 as clearly shown in Fig. 3.

30 The spokes 39 are provided with sockets 47, in which a shank 48 is slidably mounted, said shank having on its upper end a ball 49 which is mounted in the tubular spacing member and adapted to move freely therein; the shank 48 moving in the elongated slot 43. The ball 49 has a recess 50 with sides diverging, in which is pivoted one end of a 35 spear tooth 51, the other, or free end of the tooth, extending through an enlarged opening 52 in the wheel 17.

40 The disk 37^a is provided with a flange 53 which terminates in a cam face 54 at each end. The disk 45 is similar to the disk 37^a and is provided with a flange 56 terminating at each end in a cam face 57. These two disks are alike and are mounted rigidly on the spindle 36 with the flanges 53 and 56 on opposite sides of the spindle so that the 45 flange of one disk is opposite the flat portion of the disk, thus forming a continuous cam groove in which the spokes 39 move. The disk 37 with its spokes is mounted on the spindle 36 between the disk 37^a and 55 with the spokes projecting through the cam groove formed by the flanges 53 and 56. There is a series of the tubular spacing members disposed at regular intervals around the wheel 17 near its periphery, and in each is 55 mounted a spear tooth 51.

50 The operation of the machine is as follows: The machine is propelled along a row of shocks with the wheels astride the row so that the shock is positioned between the 60 pending side 3 and the wheel 17. As the center of the wheels is opposite the shock, the spear pins or teeth 51 to the rear of the center of the wheel are gradually projected through the openings 52 and pierce the shock 65 and the revolution of the wheel (the teeth

traveling with it) elevates the shock and carries it to a point immediately above the endless belt 6 when the teeth are withdrawn from the shock, thereby permitting the shock to fall upon the belt which in turn conveys it to a wagon which travels beside the loader. As the wheel 17 revolves, the disks 37^a and 55 are carried with it, which results in moving the spokes 39 in and out by means of the cam groove formed between the disks, which in return results in the ball 49 moving back and forth in the spacing member 42, the shank 48 sliding in the groove 43 and reciprocating in the socket 47, which causes the spear teeth or pins to reciprocate to pierce 80 lift and release the shock. The mechanism is so timed and the cam groove so formed that the teeth will not be projected until the shock is about the center of the machine and will be withdrawn as the shock is positioned 85 immediately above the elevator 6. The teeth are not projected simultaneously, but are gradually and successively projected. If the shocks are loosened by wind or from any other cause, the gathering wheels 28, by 90 means of the teeth 31, push them and all stray bundles in line with the path of the machine, and as soon as the teeth pass from under the plate 34 they hang loose and drag, thereby obviating all danger of dragging the 95 loose bundles out of the path of the machine. The traction wheels 29 through the bevel gear 30 serve to operate the gathering wheels by reason of its engagement with the bevel pinion 27. These gathering wheels also 100 serve to gather loose hay, etc., into the path of the machine, so that it will be in position for the pins 51 to gather it up and deposit it on the elevator 6. In the event that any material escapes the teeth 51, I provide the 105 endless carrier 18 which is driven by means of the chain 21 in a direction opposite to the travel of the machine which sweeps the material up for engagement with the teeth 51. The chain 21 is driven from the shaft 110 11, which in turn is driven from the chain 15 which receives its power from the sprocket 16 on the wheel 17. The carrier 6 is driven by means of the bevel gear wheels 10 and 13. I provide a trough or other suitable receptacle 115 at the foot of the endless carrier 6 to catch any grain that might drop from the shock as it is loaded on the carrier.

What I claim is:—

1. In a shock loader, the combination with 120 a traction wheel, of a series of teeth separately mounted for successive projection, and means to project said teeth separately to engage and lift a shock.
2. In a shock loader, the combination with 125 a traction wheel, of a series of teeth mounted said wheel, for successive independent sliding movement and means to project said teeth successively.
3. In a shock loader, the combination with 130

- 5 a traction wheel, of a series of teeth each mounted on said wheel for separate independent and successive movement, and means to successively project each tooth.

5 4. In a shock loader, the combination with a traction wheel, of a series of teeth each mounted on said wheel for separate independent and successive movement, and means mounted on said wheel to successively project said teeth.

10 5. In a shock loader, the combination with a traction wheel, of a series of teeth each mounted on said wheel for separate independent and successive movement, and means on said wheel to successively project and retract each tooth.

15 6. In a shock loader, the combination with independently slidably mounted teeth, of means to move said teeth into and out of operative position successively.

20 7. In a shock loader, the combination with a series of teeth movable independently of each other, of a spoke secured to each of said teeth at right angles thereto, and means to successively move each spoke to successively operate said teeth independently of each other.

25 8. In a shock loader, the combination with a series of teeth movable independently of each other, of a spoke secured to each of said teeth at right angles thereto, and a cam to successively move said spokes and teeth independently of each other.

30 9. In a shock loader, the combination with cam plates in juxtaposition to form a cam groove, of a series of teeth movable independently of each other and movable spokes projecting through said groove, one tooth being secured to each of said spokes through-40 out the series, whereby said teeth are each successively operated by said spokes.

35 10. In a shock loader, the combination with a guide having an elongated slot in its inner face, a ball mounted in said guide, a tooth pivotally secured to said ball, a shank on said ball projecting through said slot, a spoke having a socket to receive said shank, and means to move said spoke, ball and tooth.

45 11. In a shock loader, the combination with a traction wheel, a ring spaced therefrom and tubular guides connecting said ring and wheel, of two oppositely disposed cam disks secured to said wheel, a series of separately mounted and independently movable spokes carried by said wheel and movable by said disks, balls having a slid-50 able connection with the end of said spokes and slidably mounted in said tubular guides, and a tooth pivotally secured to each of said balls.

55 12. In a shock loader, the combination with a traction wheel a support therefor and a bevel gear carried thereby, of a gathering wheel a support therefor, said gathering

60 65 70 75 80 85 90 95 100 105 110 115 120 125 130

ering wheel being positioned over and around the front, rear and sides of the traction wheel, a pinion on the gathering wheel to engage the said bevel gear, and gathering teeth secured to said gathering wheel.

13. In a shock loader, the combination with a traction wheel a support therefor and a bevel gear carried thereby, of a gathering wheel positioned over and around the front, rear and sides of the traction wheel, a support for the gathering wheel a pinion on the gathering wheel to engage the bevel gear, gathering teeth pivotally mounted on said gathering wheel, and means to render said teeth inoperative.

14. In a shock loader, the combination with traction wheels, of gathering wheels, having gathering teeth loosely pivoted on the rim thereof, and means to hold the teeth rigid for a portion of their travel.

15. In a shock loader, the combination with traction wheels, of gathering wheels, having teeth loosely pivoted on the rim thereof, a plate rigidly mounted and positioned concentric to the rim of the gathering wheel to hold said teeth rigid for a portion of their travel.

16. In a shock loader, the combination with a frame, a traction wheel journaled to said frame, and an endless carrier mounted on said frame, of a traction wheel journaled on said frame, teeth singly mounted on said last-named wheel for separate successive and independent movement, means to project each tooth separately and successively toward said frame, and hold each in its projected position until it is over the said endless carrier and to retract each tooth successively when in that position.

17. In a shock loader, the combination with a frame, a traction wheel secured to said frame, an endless carrier secured to the rear end of said frame, and an endless carrier mounted on said frame, of a traction wheel journaled on said frame, separate teeth singly mounted on the last-named wheel for independent movement, means to project said teeth successively toward said frame, and hold them in their projected position until they are over the endless carrier on the said frame and to retract the teeth when in that position.

18. A shock loader, comprising a traction wheel, a series of separate independently and successively movable teeth carried thereby, means spaced about said wheel to which said teeth are secured, and means for moving each tooth successively and independently of the other teeth in a direction substantially parallel to the axis of the wheel, so that each tooth is moved separately and successively.

19. A shock loader comprising a supporting wheel, a series of separate successively movable parts spaced about said wheel, said

parts being independently mounted for independent movement, a series of teeth, one tooth being mounted on each of said movable parts for independent successive bodily movement, a cam for moving the teeth in a direction substantially parallel to the axis of the wheel, so that each tooth is moved bodily independently and successively.

20. A shock loader, comprising a traction wheel a series of separately mounted parts spaced about said wheel for independent movement bodily, and a single tooth connected to each of said parts, each tooth

throughout the series being movable successively, in combination with a cam to engage said parts to move them and each tooth separately and successively in a direction substantially parallel to the axis of the wheel when the wheel is rotated.

In testimony whereof I affix my signature 20 in presence of two witnesses.

GEORGE A. IMHOFF.
